(57) **CLAIM**

I claim the ornamental design for a surgical blade, as shown and described.

DESCRIPTION

FIG. 1 is a perspective view of a surgical blade;
FIG. 2 is a front side view of the surgical blade;
FIG. 3 is a rear side view of the surgical blade;
FIG. 4 is a top plan view of the surgical blade;
FIG. 5 is a bottom plan view of the surgical blade;
FIG. 6 is a right side view of the surgical blade; and,
FIG. 7 is a left side view of the surgical blade.
